COMBINED CLOTHES HOOK AND WALL
BRACKET FOR SUPPORTING A CLOSET
SHELF AND A HANGER BAR

Paul N. Nordenson, 4911 Excelsior Blvd.,
Minneapolis, Minn.

Filed Jan. 13, 1960, Ser. No. 59,040

Term of patent 14 years

(Cl. D33—3)

FIG. 1

FIG. 2

FIG. 3
FIG. 4

FIG. 4

FIG. 5

FIG. 6

FIG. 7

FIG. 8

Figure 1 is a front elevational view of a combined clothes hook and wall bracket for supporting a closet shelf and a hanger bar embodying my new design;

I claim:

The ornamental design for a combined clothes hook and wall bracket for supporting a closet shelf and a hanger bar, as shown.
